UNITED STATES PATENT OFFICE.

HENRY ADAMS, OF STAMFORD, CONNECTICUT.

CENTRIFUGAL TABLE.

1,221,951.

Specification of Letters Patent. Patented Apr. 10, 1917.

Application filed January 9, 1914, Serial No. 811,201. Renewed October 21, 1916. Serial No. 127,032.

To all whom it may concern:

Be it known that I, HENRY ADAMS, a citizen of the United States, residing at Stamford, in the county of Fairfield and State of Connecticut, have invented certain new and useful Improvements in Centrifugal Tables; and I do declare the following to be a full, clear, and exact description of the invention, such as will enable others skilled in the art 5 to which it appertains to make and use the same.

This invention relates to improvements in centrifugal tables.

The object of the invention is to provide a 15 revoluble table so constructed that separation of the material treated is accomplished by the combined influences of centrifugal force and gravitation, under the action of which, the material is deposited in regular 20 gradations in separate receptacles.

Another object of the invention is to provide a table of this character so constructed that it may be used equally well for concentration, sizing and washing of ores; treatment 25 of slimes, for amalgamating, and for the cyanid treatment of gold and silver ores.

With these and other objects in view, the invention consists of certain novel features of construction, and the combination and 30 arrangement of parts, as will be more fully described and claimed.

In the accompanying drawings:

Figure 1 represents a plan view of a table constructed in accordance with this invention;

Fig. 2 is a vertical central section thereof;

Fig. 3 is an enlarged detail sectional view of the table.

In the embodiment illustrated, a circular 40 table 1 is shown constructed of wood or other suitable material and comprises an imperforate or solid central circular portion 2 of dished form, with a substantially cone-shaped center 3, and a plurality of vertically 45 spaced series 4, 5, 6, 7 and 8 of graded planes, said planes being of annular formation.

The solid or imperforate central portion 2 of the table is fixed to a centrally disposed 50 upright shaft 9 rotatably mounted in suitable bearings B. Rotary motion may be applied to the vertical shaft 9 from any source of power in any determinate way. The centrally disposed cone 3 acts as a distributor

or a deflector to impart initial outward 55 movement to the material as it is received upon the concentrating table, a suitable spout P which extends around the shaft 9 being preferably employed to discharge the material to be treated, onto the table. 60

A table base or supporting member 10 is shown in circular form being preferably constructed of iron shafting or other suitable material and having a common center which is the main shaft 9. This base is 65 connected with the central portion 2 and with the various planes by brace rods 11 of suitable construction.

The edge of the central portion 2 is connected with the lower series of planes 8, the 70 planes 12 of which are arranged in step like form and gradually decrease in height from the member 2 outward. These planes 12 have risers 13 arranged between them and extending from the outer edge of each plane. 75 These risers are inclined downwardly and inwardly, as shown in Fig. 2 for a purpose to be described.

The planes 14 of the upper series 4 are independent of each other and increase gradually in height and in size from the center of the table toward its periphery, each being of annular formation and inclined downwardly and inwardly. Each plane 14 is provided on its inner edge with a down- 80 wardly extending lip 14' inclined toward the center of the table and extending under the outer edge of the next plane below it in the same series and which is designed, un- 85

der the action of centrifugal force, to separate the material thrown thereagainst, causing the heavier material to pass up the lip onto the plane above, with which said lip is connected, and the lighter material to pass down the lip into the opening between the 90 lip and the plane below it, and to be deposited upon one of the planes in the series next below, and this operation is repeated in the various series until the material has been thoroughly separated, as will be hereinafter more fully described. Four of the 95 planes 14 are here shown, but any desired number may be employed, according to the character of the work, and the material to be separated. 100

The series 5 is disposed below the series 4 any suitable or desired distance, and comprises three annular planes 15, decreasing in 105

size and height from the periphery toward the center of the table, and each having on its inner edge a lip 15', similar to the lip 14' of the series 4 above and which is designed 5 for the same purpose.

The series 6 is disposed below series 5 a suitable or desired distance, and comprises two annular planes 16 decreasing in size and height from the periphery of the table toward its center, and each having on its inner edge a lip 16' similar to those above described relative to the other series.

A single annular plane 7 is shown disposed between series 6 and 8 and as a lip 7' 15 at its inner edge inclined downwardly and inwardly toward the center of the table. The planes at the periphery of the respective series gradually increase in width from the top or uppermost series 4 to the lowermost series 8, as is clearly shown in Fig. 2, the other planes of the series being of the same width, but it is obvious that these proportions may be varied to meet the requirements of the material to be treated.

25 The planes of the respective series are connected by adjustable members, here shown in the form of adjustable screws or bolts 18, which serve also as spacing members for the planes of the respective series, and are adjustable to vary the distances between said series.

The planes of each series are positioned at the same angle relative to the base 10 that the central portion 2 occupies, and the lips 35 of the planes are arranged in the same angle with relation to the base 10, as is the central portion 2. The lips of the various planes are positioned at the same angle, but they may be changed if found necessary.

40 The length or width of these planes depends on the material and the capacity of the machine, and those of each set of planes underneath those above it, are arranged parallel to the ones above by increasing the width of 45 each of the outer planes of each series, as above described. The inner planes of each series will be positioned a little closer to the central shaft 9 than those in the series above it, so that the lip of the plane above will 50 discharge onto the middle of the lip of the corresponding plane in the series below it.

In the use of this centrifugal table, fine crushed ore or other material to be classified or treated, is mixed with water and run onto 55 the revolving table at the center thereof through the circular spout P which extends around the shaft 9 and the centrifugal force carries pulp or other material up over the solid inclined central portion 2, which gradually becomes thinner as the pulp spreads over greater area, and the heavier particles settle on or near the surface of the table and move upward until the pulp reaches the edge of the central portion 2, and from this 60 point, the actual separation of the material

treated begins. The thin stream of pulp falls from the edge of the central portion 2 onto the downwardly inclined lip 14' of the uppermost series of planes 4, and the centrifugal force of the tables carries the heavier 70 material up said lip along the first or innermost plane 14 to the outer edge of said plane. The lighter material falls from the lip 14' of the inner plane 14 into the opening between said lip and the riser 13 of the innermost step or plane 12 and over said plane 12 to its outer edge, and at the edge of this plane to step 12 and the outer edge of the innermost plane 14, the same operation is repeated and continued, the heavier 75 particles passing up the lips of the respective planes onto the planes above them, and the lighter particles falling downwardly through the openings between the planes onto the series next below and this operation is repeated in the respective series of planes until the material reaches the outermost planes of each series from which it falls or passes in the suitable receptacle arranged to receive it, having been classified into five 80 different sizes as shown in this apparatus, but it is to be observed that the number of the series may be varied when found necessary. The material is concentrated according to the different specific gravities of the 85 various minerals contained in the ore, from the lightest in the series 8 to the heaviest in 90 series 4.

Should it be desired to wash or treat the ore or mineral with any desired solution, the 100 circular slotted spout or spouts may be placed around the main shaft 9 to admit said solution onto the table during the feeding of the material to be treated.

From the above, it will be obvious that 105 this centrifugal table may be used for a variety of purposes, and is especially adapted for use for the concentration of ores or minerals, for the treatment of slimes, for the classification or sizing of ores or minerals, for the washing of ores or minerals, and especially for amalgamation, in which latter case, the lips and planes are made of copper 110 and the pulp from the mill passing over the revolving table by means of centrifugal 115 force, will pass up the table and over the different planes and lips, whereby every particle of the pulp will touch the copper plates, thereby obtaining a perfect amalgamation. It is also found to be especially 120 useful in the cyanid treatment of gold and silver ores, as the ore, in its passage over the planes of the table, is so separated and distributed that every particle thereof is brought into direct contact with the cyanid 125 solution, and as the pulp is exposed to the air continuously, the action of the cyanid is greatly accelerated.

The table constructed as above described, 130 may be very cheaply manufactured and may

be operated at a minimum cost and with very little trouble, as the machine, after being set in operation will automatically separate the material treated, the operator being required 5 only to see that the proper quantity of pulp is fed on to the table, and this may be automatically controlled, if desired.

I claim as my invention:—

1. A centrifugal table adapted to have rotary movement imparted thereto and comprising a concentric series of independent annular planes each inclined outward and upward from the preceding and disposed at a higher level in progressive order from the 15 center outward, and each having on its inner edge a lip inclined downwardly and toward the center of the table, each lip being so located with respect to the annular plane arranged within said lip that the material projected centrifugally from said plane will impinge on said lip intermediate its upper and lower edges.

2. A centrifugal table adapted to have rotary movement imparted thereto and comprising a central imperforate portion inclined upwardly and outwardly from its center to its periphery and a concentric series of independent annular planes arranged around said central portion and each having 30 on its inner edge a lip inclined downwardly and toward the center of the table, each lip being so located with respect to the annular plane arranged within said lip that the material projected centrifugally from said 35 plane will impinge on said lip intermediate its upper and lower edges.

3. A centrifugal table adapted to have rotary movement imparted thereto and comprising a central imperforate portion inclined upwardly and outwardly from its center to its periphery and a concentric series of independent annular planes arranged around said central portion and each having on its inner edge a lip inclined downwardly 45 and toward the center of the table, each lip being so located with respect to the annular plane arranged within said lip that the material projected centrifugally from said plane will impinge on said lip intermediate 50 its upper and lower edges, and a series of step-like planes arranged in planes below said central portion and decreasing in height from the center toward the periphery of the table, and downwardly and inwardly inclined risers each connecting the outer edge of one plane with the inner edge of the next plane below it.

4. A centrifugal table adapted to have rotary movement imparted thereto and comprising a central imperforate portion inclined upwardly and outwardly from its center to its periphery and a concentric series 60 of independent annular planes arranged around said central portion and each having on its inner edge a lip inclined down-

wardly and toward the center of the table each lip being so located with respect to the annular plane arranged within said lip that the material projected centrifugally from said plane will impinge on said lip intermediate its upper and lower edges, and a series 70 of step-like planes arranged in planes below said central portion and decreasing in height from the center to the periphery of the table, and downwardly and inwardly inclined risers each connecting the outer edge of one plane with the inner edge of the next plane below it, and a plurality of series of independent planes arranged between said upper and lower series.

5. A centrifugal table adapted to have rotary movement imparted thereto and comprising a central imperforate portion inclined upwardly and outwardly from its center to its periphery, and a concentric series of independent annular planes arranged around said central portion and each having on its inner edge a lip inclined downwardly and toward the center of the table each lip being so located with respect to the annular plane arranged within said lip that the material projected centrifugally from said plane will impinge on said lip intermediate its upper and lower edges, and a series of step-like planes arranged in 80 planes below said central portion and decreasing in height from the center to the periphery of the table, and downwardly and inwardly inclined risers each connecting the outer edge of one plane with the inner edge of the next plane below it, and a plurality of series of independent planes arranged between said upper and lower series.

6. A centrifugal table adapted to have rotary movement imparted thereto and comprising a central imperforate portion inclined upwardly and outwardly from its center to its periphery, and a concentric series of independent annular planes arranged around said central portion and each having on its inner edge a lip inclined downwardly and toward the center of the table each lip being so located with respect to the annular plane arranged within said lip that the material projected centrifugally from said plane will impinge on said lip intermediate its upper and lower edges, and a series of step-like planes arranged in planes below said central portion and decreasing in height from the center to the periphery of the table, and downwardly and inwardly inclined risers each connecting the outer edge of one plane with the inner edge of the next plane below it, and a plurality of series of independent planes arranged between said upper and lower series, the intermediate series of planes decreasing in number from the upper toward the lower 100 series.

6. A centrifugal table adapted to have rotary movement imparted thereto and comprising a central imperforate portion inclined upwardly and outwardly from its center to its periphery, and a concentric series of independent annular planes arranged around said central portion and each having on its inner edge a lip inclined downwardly and toward the center of the table each lip being so located with respect to the annular plane arranged within said lip that the material projected centrifugally from said plane will impinge on said lip intermediate its upper and lower edges, and a series of step-like planes arranged in planes below said central portion and decreasing in height from the center to the periphery of the table, and downwardly and inwardly inclined risers each connecting the outer edge of one plane with the inner edge of the next plane below it, and a plurality of series of independent planes arranged between said upper and lower series, the intermediate series of planes decreasing in number from the upper toward the lower 105 series.

ber from the upper toward the lower series, the outer planes of each series being wider than the inner planes thereof.

7. A centrifugal table adapted to have 5 rotary movement imparted thereto and comprising a central imperforate portion inclined upwardly and outwardly from its center to its periphery and a concentric series of independent annular planes arranged around said central portion and each having on its inner edge a lip inclined downwardly and toward the center of the table each lip being so located with respect to the annular plane arranged within said lip that 10 the material projected centrifugally from said plane will impinge on said lip intermediate its upper and lower edges, and a series of step-like planes arranged in planes below said central portion and decreasing 15 in height from the center to the periphery of the table, and downwardly and inwardly inclined risers each connecting the outer edge of one plane with the inner edge of the next plane below it, and a plurality of 20 series of independent planes arranged between said upper and lower series, the intermediate series of planes decreasing in number from the upper toward the lower series, and the outer planes of the respective series 25 gradually increasing in width from the upper to the lowermost series.

8. A centrifugal table adapted to have

rotary movement imparted thereto and comprising a central imperforate portion inclined upwardly and outwardly from its center to its periphery and a concentric series of independent annular planes arranged around said central portion and each having on its inner edge a lip inclined downwardly and toward the center of the table each lip being so located with respect to the annular plane arranged within said lip that the material projected centrifugally from said plane will impinge on said lip intermediate its upper and lower edges, and a series of step-like planes arranged in planes below said central portion and decreasing in height from the center to the periphery of the table, and downwardly and inwardly inclined risers each connecting the outer edge of one plane with the inner edge of the next plane below it, and a plurality of series of independent planes arranged between said upper and lower series, and means for adjusting the planes of the series 35 40 45 50 55 toward and away from each other.

In testimony whereof I have hereunto set my hand in presence of two subscribing witnesses.

HENRY ADAMS.
